UNITED STATES PATENT OFFICE.

WALTER F. McCaleb, OF DALLAS, TEXAS.

COMBINED ADDING AND LISTING MACHINE.

1,257,620.

Specification of Letters Patent.

Patented Feb. 26, 1918.

Application filed June 3, 1915. Serial No. 31,809.

To all whom it may concern:

Be it known that I, WALTER F. McCaleb, a citizen of the United States, residing in Dallas, in the county of Dallas and State of Texas, have invented new and useful Improvements in Combined Adding and Listing Machines, of which the following is a specification.

This invention relates to certain new and useful improvements in a combined adding and listing machine, and has special reference to improvements in that type of machine forming the subject-matter of my Patent No. 1,153,129, granted September 7th, 1915.

The invention has for its general object to provide an improved machine of the character referred to which shall be characterized by simplicity and economy of construction and ease and rapidity of operation. The machine forming the subject-matter of the present invention is designed to meet the wants of the trade for an inexpensive machine capable of the few simple operations involved in adding, listing and totaling, (including sub-totaling), and the novel features of the invention are concerned with mechanism for permitting these functions to be performed.

Stated more in detail, specific objects of the invention relate to improvement in sector mechanism for actuating an accumulator; to improved mechanism for actuating the accumulator as a whole toward and from the sectors; to novel listing mechanism combined with the movable sectors which actuate the adding wheels of the accumulator; to novel mechanism for controlling the movements of the sectors; and to various combinations of parts whereby the operations of the machine, as hereinafter more fully set out, are accomplished.

The invention is illustrated in the accompanying drawings, in which—

Figure 1 is a top plan view;

Fig. 2 is a view in side elevation, partly in section, the view being taken from the right-hand side of the machine, the line of section being just inside the side frame;

Fig. 3 is a view similar to Fig. 2, the line of section being approximately through the middle of the machine;

Fig. 4 is a top plan view of the mechanism, the case being in horizontal section;

Fig. 5 is a fragmentary longitudinal sec-

tion illustrating the action of the restoring mechanism for the sectors;

Fig. 6 is a fragmentary longitudinal section illustrating the parts associated with the "total" key;

Fig. 7 is a fragmentary longitudinal section illustrating the action of the "carry-over" mechanism and parts of the printing mechanism;

Fig. 8 is a fragmentary section through the printing mechanism, showing the hammer trippers in the position they assume after the hammers have been tripped;

Fig. 9 is a detail view of the mechanism for limiting the speed of the main actuating shaft and for restoring the shaft to normal position; and

Fig. 10 is a fragmentary plan view, on an enlarged scale showing the hammer trippers for the printing mechanism.

Referring now to the drawings, the numerals 1, 2, indicate side frame members which are substantially triangular in shape, and are connected at their rear ends, (Fig. 6) by a cross rod 3, at their front ends by 80 a shaft 4 journaled in screw bearings 5, and at their apexes by a rock shaft 6 journaled in said frame members and retained in position by screws 7. The frame members 1, 2, are secured on opposite sides of a 85 rectangular base 8, and when in use the mechanism as a whole is covered by a casing 9 supported on said base and secured thereon in any suitable manner, as by screws. The casing 9 is preferably provided with 90 side panels 10 of glass permitting observation of the mechanism. Journaled at opposite ends in the side frame members 1, 2, is a main actuating shaft 11, to one end of which is removably connected a crank handle 12, the head 13 of which projects through an opening in one of the side panels 10 (Fig. 4). Rotatably mounted on the shaft 11 are a series of hubs 14 (Figs. 3, 4 and 5) from one side of each of which extends forward an integral arm 15, and extending upward from the outer end of this arm is a curved sector 16 provided on its outer edge with ten gear teeth 17 and on its inner edge with an equal number of curved recesses 18. 95 Projecting rearward from each hub is an integral arm 19 carrying at its outer end a listing sector 20. The arm 19 of each hub does not lie in the same vertical plane with the corresponding arm 15 of the hub, but 100 105 110

said arms 19, as shown by Fig. 4, occupy a position of relatively close proximity to each other for the purpose of the listing operation, whereas the arms 15, with their 5 sectors 16, are separated from each other by a considerable space. To effect the close proximity of the arms 19, said arms, on opposite sides of the longitudinal center of the machine, are bent inward to a greater or less 10 extent, depending upon the distance of the hub 14 from the center of the shaft 11, said bent portions being indicated by the numeral 21. It will be understood that the sector 16, arm 15, hub 14, arm 19, with its 15 bent portion 21, are in each instance formed as parts of a unitary, and preferably integral, structure, so that the sector 20 moves in unison with the sector 16. The major portion of the sector 20 is also preferably 20 formed integral with the arm 19. Suitable spacing rings 22 are interposed between the hubs 14.

Pivoted mounted on the cross shaft 6 at the top of the machine (Fig. 3) are a series 25 of dogs 23, corresponding in number to the sectors 16, and each of which has an arm 24 on the outer end of which is mounted a friction roller 25 which is adapted to releasably engage in the various recesses 18 of the corresponding sector 16. The roller 25 of each 30 dog is held in yielding engagement in one or the other of said recesses 18 by means of a short coil spring 26 connected at one end to the rear end of said dog, at its lower side, 35 and at its opposite end to a clip 27 mounted on a cross shaft 28 extending between and mounted in the side frame members 1, 2, of the machine. In order to provide for the fall of each sector 16 when totals are to be 40 taken and the adding wheels returned to zero, I connect one end of a coil spring 29 to the rear end and upper side of each dog 23, and the other end of said spring to the portion of the arm 19 to the rear of the 45 shaft 11, the springs 29 tending constantly to elevate the arms 19 with their sectors 20 and lower the arms 15 with their sectors 16. This tendency is normally overcome by the 50 engagement of the rollers 25 in the recesses 18. In order to provide for simultaneously releasing all of the rollers 25 from engagement with the recessed edge of the sectors 16 I employ the following mechanism:

Secured on the rock shaft 6 is a hub 30 55 (Fig. 6) having an upward-extending integral lever 31 and a downward-extending integral arm 32, the lever 31 extending through a slot 33 in the front wall of the casing 9 and being provided with a suitable 60 button 34 for depressing it. Secured at one end in the arm 32 at a slight distance from the rock shaft 6 is a rod 35, the opposite end of which is secured in the end of a crank plate 36 (Figs. 2 and 4) secured on the 65 opposite end of the cross shaft 6 from that

having the hub 30 secured thereon. The rod 35 extends across the machine immediately over the upper edges of the arms 24 of the dogs 23 (Fig. 3), and by depressing the lever 31 the rod 35 will be forced against 70 the arms 24 to move them rearward, thereby simultaneously releasing all of the rollers 25 from engagement with the serrated inner edges of the sectors 16, and permitting the 75 springs 29 to draw said sectors downward. 75

Each of the listing sectors 20 comprises a curved head 37 provided with ten grooves 38 in each of which is mounted a type-bar 39 provided with a digit 40 on its outer end, the digits running in order from the top to 80 the bottom of the sector from 0 to 9. Each of the type-bars 39 is provided on its side with a stud 41 which projects through a slot 42 in a curved cover plate 43 secured to the grooved side of the head 37, and extending 85 over the type-bars. A coil spring 44 is secured at one end to each stud 41 and at its opposite end to a stud 45 mounted on the side of the cover plate 43. When in the normal or lower position shown in Fig. 3, 90 the upper type-bar 39 of each of the listing sectors is in a horizontal position, and the grooves 38 in the sector head are so inclined that each of the remaining type-bars will be brought, in order, to a horizontal position as the listing sector is raised. When 95 in the horizontal position, each type-bar 39 will be opposite a platen 46 (Figs. 2 and 3) with which co-operates a feed roll 47. The numeral 48 indicates one of two similar 100 supports mounted on the casing 9 for holding a roll of paper 49, the paper being passed from the roll 49 over a guide 50, between the rolls 46 and 47, and under the platen guides 51, in the usual manner. A suitable inked 105 ribbon is carried by feeding spools 52 (Fig. 1) in the usual way, and such ribbon in practice will extend between the paper on the platen and the ends of the type-bars carrying the digits. I have not shown this 110 part of the machine in great detail as the particular paper and ribbon feed mechanism employed forms no part of the present invention.

Each of the adding wheel sectors 16 is 115 provided at its upper end with an integral arm 53 which extends through a slot 54 in the front wall of the casing 9, and is provided on its outer end with a button 55 to facilitate ready movement of the sectors by 120 the operator. Adjacent to each of the slots 54 (see Fig. 1) there is secured a strip 56 having digits thereon running in order from the upper to the lower end of the strip from 0 to 9. At the bottom of each strip 56 a circular opening 57 is made in the wall of the casing through which the digits on the adding wheels, hereinafter referred to, may be 125 readily seen. These openings, as will be understood, are of a size to render visible only 130

the digit on the adding wheel appearing directly opposite the opening. A "period" 58 may be represented in any suitable fashion on the casing (Fig. 1) to separate the two 5 apertures 57 at the right of the machine, through which digits indicating "cents" would appear, from the three apertures, in order, to the left, through which digits indicating, respectively, units, tens and hundreds will appear; and a "comma" 59 may in like manner be represented on the casing to separate the aperture, indicating hundreds, from the last aperture to the left, indicating thousands.

15 I will now describe the accumulator mechanism by means of which the operation of adding is performed:

The numerals 60 and 61 (Fig. 4) indicate, respectively, the side frame members of the 20 accumulator, and mounted therein is a shaft 62 on which the adding wheels 63 are journaled. Secured on the side of each of these adding wheels is a pinion 64 which is in line with a sector 16, each of these pinions having 25 ten teeth. Secured in turn to the side of each pinion is a ratchet wheel 65. The numeral 66 (Fig. 3) indicates one of a series of pawls which are pivotally mounted intermediate their ends on a rod 67 extending 30 between and mounted at its ends in the side frames 60, 61, of the accumulator, said pawls having their upper ends held in yielding contact with the teeth of the pinion 64 by means of coil springs 68 connected at one 35 end to the lower end of each pawl, and at its other end to a rod 69 extending between and mounted at its ends in the side frame members of the accumulator. It will be understood that a pawl 66 is provided for 40 each pinion 64. Their purpose is to prevent accidental turning of the pinions. They, however, permit the pinions to be readily turned by the sectors 16. Projecting from one side of each adding wheel 63, and located 45 near the periphery thereof, is a stud 70, which, in the rotation of the adding wheels, serves to release the carry-over mechanism, later referred to, to permit it to operate. The side frame members 60 and 50 61, between which the accumulator mechanism, as a whole, is mounted, are fixedly secured on the journaled shaft 4 previously referred to.

Extending between and fixedly secured at 55 its ends in the side frame members 60, 61, of the accumulator, near the bottom thereof, is a rod 71 (Figs. 2, 3 and 7) on which rod are pivotally mounted a series of carry-overs 72. The movement of each of these 60 carry-overs is controlled by a spring 73, one end of which is connected to a stud 74 on the carry-over and the other to a segmental plate 75 loosely mounted on the rod 67. The springs 73 tend to draw the upper end of 65 each carry-over inward or toward the add-

ing wheels. Pivotally mounted at 76 on the upper end of each carry-over is a carry-over pawl 77 which is pivoted intermediate its ends, its rear end having one end of a coil spring 78 connected thereto, the opposite end 70 of which latter is connected to the carry-over. Projecting from one side of each carry-over is a stud 79 against which engages a lug 80 on the pawl 77 (Figs. 3 and 7), the spring 78 normally holding it in this 75 position. The other end of the carry-over pawl 77 is provided with a finger 81 which is adapted in operation to engage one or the other of the teeth of a ratchet-wheel 65 to rotate its adding wheel 63, and above this 80 finger the pawl is provided with a shoulder 82 which is adapted to engage a flat portion 83 between the teeth of the ratchet-wheel to arrest the movement of the latter.

Pivotally mounted at 84 on the side of 85 each carry-over is a guard 85, the upper end of which is bent to project over a curved lateral off-set 86 provided intermediate the ends of the carry-over, the projecting portion of the guard being indicated by 87 90 (Fig. 3). The guard 85 has at its lower end an integral arm 88, to the outer end of which is connected one end of a coil spring 89, the upper end of which latter is connected to the under side of the off-set portion 95 of the carry-over. Extending between and secured at its ends in the side frame members 60, 61, of the accumulator is a rod 90 on which are journaled a series of carry-over locks 91, one of these carry-over 100 locks being provided for each adding wheel and its corresponding carry-over. The carry-over lock 91 has at one side an arm 92 which projects upward between two adjacent adding wheels, and is adapted to be 105 engaged by the stud 70 on one of said adding wheels to release the carry-over. Projecting laterally from the opposite side of the carry-over lock is a dog 93, the outer end of which is normally held in engagement with a shoulder 94 (see Figs. 2 and 3) on the off-set 86 of each accumulator by means of a spring 95, one end of which is secured to the dog and the other end to the segmental plate 75 before referred to. 110 Mounted on the carry-over member 72, near the inner end of the curved off-set 86, is a stud 96. The guard 85 normally engages the outer end of the dog 93, but when said dog is raised by a stud 70 on an adding wheel engaging the arm 92, the guard 85 springs inward against the stud 96 and under the end of said dog 93, so that the dog in the movement of the carry-over, as 115 later described, will ride over the shoulder 94 and not engage it.

The numeral 97 (Figs. 3 and 4) indicates a rod mounted at its ends in the opposite side frame members 60 and 61, which rod acts as a stop to limit the movement of the 130

carry-overs when they are drawn outward by the carry-over restorer, as hereinafter described. Each of the carry-overs 72 has a curved portion 98 (Fig. 3) forming a 5 nose-piece projecting below the rod 71; and in the path of a slide-plate 99, which acts as a carry-over restorer. This slide-plate (see Figs. 3 and 4) is provided near each end with a slot 100, in which is located the 10 shouldered portion 101 of a screw-stud 102, the head of which is large enough to extend over the slot and hold the carry-over restorer plate 99 in slidable relation on the base 8 of the machine. The numerals 103 15 indicate studs located on the base 8 of the machine near the opposite ends of the carry-over restorer plate 99, and the numerals 104 similar studs located on said plate 99 near opposite ends thereof. Coil springs 105 are 20 connected at their opposite ends to these respective pairs of studs, and tend normally to hold the plate 99 in a normal retracted position, or in that position in which it is farthest removed from the nose- 25 pieces 98 when the latter are in normal position, such position being shown in Figs. 2 and 3.

Adjustably mounted on studs 106 located on the carry-over restorer plate 99 30 adjacent to the studs 104 are two connecting rods 107 (Fig. 7) which extend rearward and are connected at their ends to downward-extending members 108 of a bell-crank levers 109, which latter are respectively pivoted as at 110, on a bracket member 111, which is secured to the base 8 of the machine. Secured on the main actuating shaft 11 are two crank arms 112, each of which has pivotally mounted on its lower end, 40 as indicated at 113, a toggle member 114, the toggle member being pivoted intermediate its ends and constituting a dog. This toggle member occupies normally an inclined or broken relation with respect to the crank arm 112, as shown in Figs. 2, 45 and 7. A coil spring 115 connects the upper end of the toggle member 114 with the crank arm 112, tending normally to straighten said toggle member with respect 50 to the crank arm. The other member 116 of the bell crank levers 109 is provided at its outer end with a stud 117. The lower end portion of the toggle member 114 is provided with a shouldered recess 118 55 which normally engages said stud 117, being held in such position by the spring 115. In the first movement of the crank handle 12 in the forward direction the crank arms 112 will be turned toward the rear, and in 60 this movement the toggle members 114 will be straightened with respect to the crank arms 112, as shown by the dash lines in Fig. 7, thereby turning the bell crank levers 109 and drawing the carry-over restorer 65 plate 99 toward the nose-pieces 98; and this

movement continues until the shouldered recess 118 rides off of the stud 117, when the springs 105 will immediately return the carry-over restorer plate 99 to normal position.

A sector (one or more) 16 having been depressed, the next main operation will be that of effecting the engagement between the accumulator and the sector depressed, or if more than one sector has been depressed, of all of the sectors so affected. To accomplish this, the mechanism is employed which will now be described.

The numeral 119 indicates a stub shaft mounted on the side frame member 1 of the 80 machine (more clearly shown in Figs. 4 and 6) and on this stub shaft is journaled a bell crank lever 120 having the extremities of its arms 121, 122, connected by an integral angular cross member 123. Journaled on 85 the main actuating shaft 11 is a crank arm 124 which has pivotally mounted at 125, on its outer end, a toggle member 126, said toggle member being pivoted intermediate its ends, and its outer end, in turn, being pivotally connected, as at 127, to the outer end of the arm 122 of the bell crank lever 120. A coil spring 128 connects the other end of said toggle member 126 with the crank arm 124. The parts just described are normally 90 in the position shown in Fig. 6, that is to say, with the toggle broken. A crank arm 129, similar to the crank arm 124, is also journaled on the shaft 11, and has pivotally mounted on its outer end, as indicated at 100 130, a toggle member 131, similar to the toggle member 126. The outer end of this toggle member 131 is pivotally connected, as indicated at 132, to the outer end of the arm 121 of the bell crank lever 120. A 105 spring 133, corresponding to the spring 128, tends normally to straighten the toggle member 131 with reference to the crank arm 129. Such movement of the toggle member 131 is limited by a stud 134 on the 110 crank arm 129 to which one end of the spring 133 is secured. In a similar way, the straightening movement of the toggle member 126 is arrested by a stud 135 on the 115 crank arm 124 to which one end of the spring 128 is secured.

Pivotally connected, as at 136, centrally of the member 123 which connects the outer ends of the arms 121, 122, of the bell crank 120, is a lever arm 137 which acts as the 120 accumulator control-bar, that is to say, to draw the accumulator pinions 64 into mesh with the sectors 16 and to move them out of mesh at the appropriate times. The free end of the lever arm or accumulator control-bar 137 is enlarged, as shown, and is provided with a recess 138 on its upper side and a recess 139 on its lower side. Projecting from the side frame member 60 of the accumulator is a stud 140 located toward 130

the upper part of the frame, and the recess 138 on the upper side of the accumulator control-bar 137 normally engages this stud.

Toward the bottom of the same side frame 5 member of the accumulator is a similar stud 141 which is adapted to be engaged by the recess 139 of the bar 137 when the same is moved downward, as later described. Pivotally connected at 142 to the accumulator 10 control-bar 137 is the lower end of a link bar 143 whose upper end is pivotally connected to the lever 31. A spring 144 is secured at one end to the accumulator control-bar 137 and at its opposite end to a clip 145 15 mounted on the cross shaft 28. This spring holds the accumulator control-bar 137 normally with its recess 138 in engagement with the stud 140 of the accumulator.

Fixedly secured on the main actuating 20 shaft 11 is a double dog or tappet 146 having arms 147 and 148 projecting on opposite sides of said shaft. Mounted on the crank arm 124 is a stud 149 with which the dog 147 normally engages. A similar stud 150 25 is provided on the crank arm 129. As the crank handle 12 is drawn forward the first action which occurs is the movement forward and return of the slide-plate 99, as previously described. As the movement forward 30 of the crank handle continues the dog 148 will engage the stud 150 on the crank arm 129, and by moving said crank arm inward, break the toggle joint and move the toggle member 131 downward against the 35 resistance of its spring 133. This movement of the crank arm 129 causes the bell crank 120 to be rocked rearward, thereby drawing the accumulator control-bar 137 in the same direction and pulling the accumulator 40 rearward through engagement of the control-bar with the stud 140 until its pinions 64 engage with the sectors 16 which have been depressed. As this engagement is effected the toggle member 126 will have 45 assumed a straight position with respect to the crank arm 124, and thereby serves to temporarily lock the accumulator pinions in mesh with the sectors.

The lower inner side of the frame member 50 60 of the accumulator is provided with an extension 151 (Figs. 3 and 7) having two semi-circular recesses, an upper one 152, and a lower one 153, and a further yielding locking means for the accumulator 55 is provided by a bell crank 154 which is journaled on a stub shaft 155 mounted on the adjacent side frame 1 of the machine, one arm 156 of said bell crank being provided at its outer end with a roller 157, and 60 the outer end of the other arm 158 being connected to one end of a coil spring 159, whose opposite end is connected to a lug 160 on the base 8 of the machine. The spring 159 holds the roller 157 in yielding contact 65 with the accumulator frame member 60 so

that said roller will yieldingly engage in one or the other of the recesses 152, 153, according to whether the accumulator is moved into or out of engagement with the sectors. The purpose of this yielding locking mechanism is to maintain the accumulator in the position to which it may have been moved by the accumulator control-bar 137 at such times as said bar may be moved out of engagement with one or the other 70 of the studs 140 and 141. Accordingly, as the accumulator is moved into engagement with the sectors, as above described, the roller 157 will move into the upper recess 152.

Referring now more particularly to Figs. 80 4 and 9, the numeral 161 indicates a clip which engages an annularly recessed portion 162 of a stud 163 which projects inward from the lower rear portion of the side frame 1 of the machine. To the clip 85 161 is secured one end of a spring 164 whose opposite end is secured to a clip 165 which is hooked over a stud 166 on one arm 167 of a lever member 168, which latter is fixedly secured on the main actuating shaft 90 11. Swiveled on the cross rod 3 is a dash-pot comprising a cylinder 169 in which works a piston 170, said piston having a passageway 171 therethrough to permit the passage of oil or other liquid within the 95 cylinder from one side of the piston to the other. The piston has a stem 172 which is pivotally connected at its outer end, as at 173, to the opposite arm 174 of said lever member 168. These parts just described 100 constitute the controlling mechanism for the main actuating shaft 11. As the crank handle 12 is drawn forward the lever member 168 is rocked, thereby extending the spring 164 and causing the piston 170 to 105 move inward in the cylinder 169. The cylinder being supplied with oil or other suitable fluid, the speed of movement of the crank arm 12 will be retarded by the necessity of the piston forcing the oil in front 110 of it through the passageway 171 into the opposite end of the cylinder. As the pull on the crank handle 12 is released the spring 164 effects the return movement of the parts, the speed being controlled by the dash-pot 115 in the same manner as when the handle is being pulled forward.

In order to compel the operator to complete the stroke of the crank handle in either the forward or return operations, a sector 120 plate 175 (see Figs. 2 and 4) is fixedly secured on the main actuating shaft 11. On the outer face of the sector plate 175 is a segmental rack 176 having a series of peripheral recesses 177 therein, and pivotally 125 mounted on a stub shaft 178 projecting inward from the side frame 2 is a pawl 179 whose end portion projects into the path of the rack 176 so as to engage in the recesses 177 when the sector plate 175 is moved in 130

either direction. Said pawl 179 is held in normal position by a coil spring 180 which is fastened to a lug 181 on the base 8 of the machine. By this arrangement, if the crank 5 handle should be released during the movement in either direction the engagement of the pawl 179 with the rack 176 will prevent the movement in the opposite direction until the rack has moved clear of said pawl. The 10 sector plate is provided at opposite ends with projections 182 and 183, the one, 182, engaging the stub shaft 178 and serving as a stop to limit the rearward stroke of the operating handle, and the other, 183, likewise engaging said stub shaft 178 to limit the forward stroke of the handle.

Journalized loosely on the main actuating shaft 11 near the opposite ends thereof are two lever arms 184 (see Figs. 2, 4 and 5) 20 which are connected near their outer ends by a cross rod 185. Pivotedly connected to each of the arms 184, as at 186, is a link bar 187 which is, in turn, pivotedly connected to the end portion of an arm 188 of a bell 25 crank 189, as at 190. The opposite arm 191 of the bell crank is provided with a toe portion 192 arranged and adapted to rest normally upon the base 8. The bell cranks 189 are yieldably held in normal position by 30 springs 193, said springs being attached at one end to the arms 188 and respectively attached at their opposite ends to the stud 163 projecting from the side frame 1, and a special stud 194 projecting from the side frame 35 2, as more clearly shown in Fig. 4. In the normal position of the parts, as more clearly shown in full lines in Fig. 5, the cross bar 185 is in a position to be engaged by the sector arms 15 when the sectors 16 are depressed to their lowermost position. Fixedly secured on the main actuating shaft 11 adjacent to each of the arms 184, are lever arms 195, said arms 195 having toggle members 196 pivotally mounted on the ends 40 thereof. The toggle members 196 are yieldingly held in normally straightened position with respect to the arms 195 by springs 197 which are attached to studs 198 on the arms 195 and to studs 199 on extensions 200 45 of said toggle member 196, said extensions 200 bearing normally against the studs 198. Said toggle members 196 are provided with shouldered recessed portions 201 which are adapted to engage rollers 202 which are 50 journalized on extensions 203 of the arms 188 of the bell cranks 189. As the crank handle 12 is moved forward the arms 195 carrying the toggle members 196 swing rearward and upward, the members 196 riding 55 over the rollers 202, causing the toggle members 196 to break or assume an angular relation with respect to the arms 195, the final position of the parts when the crank handle 60 is in its extreme forward position being best 65 shown in dot and dash lines in Fig. 5, the

shouldered recessed portions 201 being in coöperative relation to the rollers 202 so as to engage the latter on the return stroke of the crank handle. As the crank handle moves rearward the recessed shouldered portions 201 engaging the rollers 202 cause the toggle members 196 to straighten with respect to their lever arms 195 and thereby rock the toggle members 189, and through the connecting links 187 the pivotal arms 75 184 will swing upward, and the cross rod 185 will raise all of the sectors 16 which have been depressed, to normal position. Just before the crank handle reaches the end of its rearward stroke the toggle members 80 196 will move out of engagement with the rollers 202, and the springs 193 restore the toggle members 188 and the parts connected thereto to normal position. During this actuation the pinions 64 which are in mesh 85 with the sectors will be rotated to advance the digits on the adding wheels 63 a distance corresponding to that to which the sectors have been depressed. In the continued rearward movement of the crank handle, and after the sectors have been restored in the manner just described, the dog 147 will engage the stud 149 and break the toggle 124, 126, at 125, and thereby move the bell crank 120 with the accumulator control-bar 137 toward the front of the machine, which latter bar, through engagement with the stud 140 of the accumulator, acts to move the pinions 64 out of mesh with the sectors 16. At the completion of this movement the toggle member 131 straightens and engages the stud 134 on the arm 129 and thereby locks the accumulator in the outward, or inoperative, position. In the preceding operation, where the adding wheels 100 63 have been turned by the rise of the sectors 16, if a sector has been depressed to a digit in a column which, added to the digit on the adding wheel of that column appearing through the sight opening 57, will 105 amount to more than nine, the stud 70 on such adding wheel will engage the arm 92 of the carry-over lock 91, and raise the dog 93 so that the guard 85 will spring inward against the lug 96 to carry its end 87 under 110 said dog. This occurs while the sectors are moving upward and while in mesh with the pinions 64 of the accumulator. As the sectors are restored to normal, the carry-overs 72 are prevented from being drawn 115 inward by their springs 73, by reason of the fact that the nose-pieces 98 of the accumulators are in engagement with the forward edge of the slide-plate 99. After the sectors have been fully raised, however, the accumulator frame will then be rocked outward by means of the accumulator control-bar 137, in the manner previously described. In this rocking movement of the accumulator the nose-piece 98 will be turned out of 120 130

engagement with the slide-plate 99, and the carry-overs, released by the carry-over lock 91, in the manner described, will be drawn inward by their springs 73. In this movement of the carry-over the finger 81 of the carry-over dog 77 will engage a tooth of the ratchet-wheel 65 of the adjacent adding wheel, and thereby advance said adding wheel one digit, such inward position of the 5 carry-over with the carry-over dog in the locking position being shown in Fig. 7. Such carry-overs as will thus have been permitted to move inward will now have their nose-pieces 98 in engagement with the forward edge of the slide-plate 99, as shown also in Fig. 7. In the next forward movement of the crank handle the slide-plate 99 will be drawn rearward and then released in the manner heretofore described, said slide- 10 plate in its rearward movement turning the carry-overs 72 outward a sufficient distance to permit the dog 93 of the carry-over lock 91 to fall behind the end 87 of the guard 85, and in front of the shoulder 94, and as 15 the slide-plate 99 snaps back to normal position the springs 73 of the carry-overs will then draw them slightly toward the adding wheels so that the dogs 93 will again engage the shoulders 94 of the carry-overs.

20 The mechanism by which the printing or listing is accomplished will now be described. Pivoted loosely on the main actuating shaft 11 is a short lever arm 204 (Figs. 2 and 7) to which is pivotally connected, as at 205, 25 one end of a connecting link 206, whose opposite end is pivotally connected to a lever arm 207 fixedly secured on the end of a rock shaft 208 extending through and journaled on two side frame members 209 constituting 30 the support for the hammer mechanism to be presently described. The arm 204 and link bar 206 constitute a toggle for effecting the actuation of the lever arm 207. Fixedly secured on the main actuating shaft 11 is a 35 double dog or tappet comprising arms 210 and 211. Normally, the tappet 210 engages a stud 212 at the point 205 between the members 204 and 206, thereby breaking the toggle, as shown more clearly in full lines in 40 Figs. 2 and 7, when the crank handle 12 is in its rearmost position; and the arm 211 is positioned with respect to the arm 210 so as to engage the stud 212 and effect the straightening of the toggle when the crank handle 45 has reached the limit of its forward stroke, which position is more clearly shown in dot and dash lines in Fig. 7, and during which actuation the lever arm 207 is moved rearward.

50 Fixedly secured on the end of the rock shaft 208 opposite to that on which the lever arm 207 is mounted is a second lever arm 213 (Fig. 8) corresponding to said lever arm 207. Connecting the upper ends of the lever arms 207, 213, is a rod 214, having pivotally 55 mounted thereon a series of dogs 215. Projecting from each of the dogs 215 is a toe piece 216 adapted to slidably engage the arcuate lower end portion 217 of the respective heads 37 of the listing sectors 20, said sectors serving to normally hold the dogs 215 in raised position. Pivotaly mounted on a cross shaft 218 between the side frame members 209 are a series of hammer actuators 219 which are enlarged at their outer ends 60 to provide heads 220. These heads are provided on their under sides with shoulders 221, and beyond said shoulders are upward-inclined nose-pieces 222. The heads 220 have upward extensions terminating with catches 65 or hooks 223 which are normally engaged by similar catch portions 224 provided on tripper members 225. These tripper members are journaled on a cross shaft 226 mounted in the side frame members 209 and said 70 tripper members are provided on their upper sides with inclined shoulders 227. The dogs 215 are provided near their ends with downward-projecting shoulders 228, inclined like the shoulders 227 on the trippers, 75 the dogs serving as actuators for the trippers in a manner as will presently more fully appear. It will be understood that there will be as many hammer actuators and trippers as there are hammers to be actuated, 80 and that the description of one unit of this mechanism will apply to all of the hammer trippers and actuators. Each of the trippers 225 is provided with a forward-extending arm 229, to the outer end of one of which 85 (the one on the right) is secured the end of a spring 230 (Figs. 3 and 7) whose opposite end is attached to a rod 231 extending between the side frame members 209. Beginning to the left of the first arm 229 on the 90 right, (see Fig. 10) each arm in its order is provided on one side with a laterally projecting finger 232 which projects under the adjacent arm to the right, so that as each arm, except the first one at the right, is 95 raised, it will raise one or more arms to the right, until, when the last arm on the left is raised, all of the arms will be raised by the engagement of each finger 232 with an adjacent arm to the right. A cross shaft 233 100 is mounted at its ends in the two side frame members 209, and on this shaft is journaled a series of hammers 234, one hammer being provided for each type sector. Each hammer is provided at its upper end with a 105 hammer head 235 with its operative face so inclined that it will strike flush against the end of a type bar. At its lower end each of these hammers is provided with a crank extension 236 extending rearward of the shaft 110 233 and being provided with a recess 237 in which engages a stud 238 secured on the adjacent hammer actuator 219. When in normal position all of the hammer actuators 115 lie with their shoulders 221 above a cross rod 120 239.

239 which is mounted on the upper ends of lever arms 240, which are, in turn, mounted on a cross rod 241 which is journaled in the side frame members 209, said lever arms 240 being connected below their pivotal axes with the lower end portions of the lever arms 207 and 213 by links 242 whereby, when the said lever arms 207, 213, are rocked, a like motion is imparted to the lever arms 240 so as to move the cross rod 239 from under the shoulders 221 of the hammer actuators 219.

In operation, one or more of the sectors 16 having been depressed, the corresponding type sectors 20 will be raised out of engagement with the extensions 216 of the corresponding dogs 215, permitting the dogs to drop so as to bring their inclined shoulders 228 into position to engage the inclined shoulders 227 on the tripper 225. As the crank handle 12 is pulled forward the dog or tappet 211 will be moved rearward into engagement with the stud 212 thereby straightening the toggle 204, 206, and moving the lever arm 207 rearward. This acts to impart a similar motion to the lever arms 240 by reason of the pivotal link connections 242 between the lever arms 207, 213, and 240, and whereby the cross rod 239 is moved from under the shoulders 221 of the hammer actuators 219. In this same movement the shoulders 228 of the dogs 215 will engage the shoulders 227 of the trippers 225 and the trippers are thereby rocked until their catches 224 are turned out of engagement with the catches 223 of the hammer actuators 219, whereby the hammer actuators so released will be at once drawn down by coil springs 243 against a stop bar 244 secured at its ends to the side members 209. In this movement of the hammer actuators each stud 238 on a released hammer actuator 219, will engage the bottom of the recess 237 of the crank extension 236 and throw the hammer head 235 rearward to effect the printing operation. By reason of the enlargement of the slot 237, after the hammer head has struck, it will be permitted to slightly rebound. This prevents a prolonged contact of the ribbon with the paper which would tend to blur the impression of the type. The printing operation just described occurs after the sectors 16 have been depressed, and the type sectors 20 correspondingly raised, and both sets of sectors are at rest. In the foregoing operation, if a single sector 16 to the left of the first column of numbers is depressed, all of the arms 229 to the right of the hammer actuator released by the upward movement of the type-sector 20 of such depressed sector will be raised by the fingers 232 to trip the other hammer actuators to print all zeros; or, if sectors 16 in the other columns have been depressed, to print zeros from all in-

termediate type sectors to the right which have not been raised. The actuation of the hammer mechanism above described is effected during the forward movement of the crank handle. As the latter is returned to normal position the tappet 210 will engage the stud 212 and break the toggle 204, 206, moving the lever arms 207, 213, and 240 back to normal position, thereby moving the cross rod 239 into contact with the nose-pieces 222 of the hammer actuators 219, and raising all of the hammer actuators, or such as have been actuated, to normal position. In this movement, the dogs 215 are drawn forward, permitting the arms 229 of the trippers 225 to be drawn downward by the spring 230, which, of course, through the medium of the fingers 232, will serve to draw down all of the arms 229 which may have been raised in the manner previously described, and again bring the catches 224 in position under the catches 223 of the hammer actuators 219. The type sectors 20 which may have been raised are now lowered by the restoration of the sectors 16 to normal position, through the mechanism described more particularly in connection with Fig. 5 of the drawings, and the arcuate end portions 217 of the sectors 20 engage the toe portions 216 of the dogs 215 and thereby lift the latter to the elevated or normal position. As the hammer actuators 219 are raised by the restorer bar 239 the studs 238 engage the upper wall of the recesses 237 of the hammer extensions 236 and throw the hammers forward to normal position.

The operation of obtaining a total will now be described.

Fixedly secured on the main actuating shaft 11 is a stop plate 245 (Fig. 6) which projects forward from the shaft, its outer end portion being arcuate and in the path of a roller 246 mounted on a stud 247, at the lower end of the arm 32 of the lever 31. Normally, the end of the stop plate 245 is at a distance from the roller 246 sufficient to permit the lever 31 to be depressed just far enough to effect the disengagement of the slotted portion 138 of the accumulator control-bar 137 from the stud 140 and also to prevent the engagement of the slotted portion 139 with the stud 141. By this arrangement of the stop plate 245 it is necessary to pull the crank handle 12 forward a short distance before the lever 31 may be fully depressed. During this initial movement of the crank handle the slide-plate 99 has been actuated to restore the carry-overs 72 to normal through the action of the toggle member 114 and bell crank 109, as previously described. When the shaft 11, however, has been turned a sufficient distance to carry the stop plate 245 out of the path of the roller 246, the lever 31 may be fully depressed to bring the recess 139 into en-

gagement with the stud 141, to depress said stud to the position shown in dotted lines in Fig. 6, which operates to rock the accumulator as a whole on its shaft 4 so as to bring the pinions 64 into mesh with the sectors 16. The lever 31 is held depressed to maintain the recess 139 in engagement with the stud 141. As the lever 31 is depressed to its fullest extent the cross rod 35 engages the arms 24 of the dogs 23 thereby moving the friction rollers 25 out of engagement with the respective recesses 18 of the sectors 16, whereupon the springs 29 move the sectors downward, rotating the adding wheels until the studs 70 come in contact with the upper ends of the arms 92 of the carry-over locks 91, when the further motion of the adding wheels and also of the sectors will be arrested. In this movement, the type sectors 20 will be raised a distance corresponding to the distance the various adding wheel sectors 16 descend, and the printing operation occurs in the manner previously stated. Immediately after the operation of printing, the dog 148 will engage the stud 150 of the crank arm 129, and by rocking the bell crank 120 rearward, as previously described, will throw the accumulator out of engagement with the sectors 16, owing to the engagement of the recessed portion 139 with the stud 141. After the pinions 64 are disengaged from the sectors 16 the latter are moved down into engagement with the cross bar 185 by the springs 29. This occurs just before the crank handle 12 reaches the end of its forward stroke. On the return stroke of the crank handle the bar 185 is raised by the engagement of the toggle members 196 with the rollers 202 on the extensions 203 of the bell cranks 189, as previously described, thereby restoring the sectors to normal position. The total has now been printed, the accumulator cleared, and the entire mechanism is at normal, so that the machine is in condition for the setting down and listing of another sum.

The operation of taking a sub-total will now be described.

In this operation the lever 31 is depressed the same as in taking a total, except that it is released just after the sectors 16 have been released in the manner previously described to rotate the adding wheels 63 back to zero position, or in other words, with their studs 70 in contact with the upper ends of the arms 92 of the carry-over locks 91. As the lever 31 is thus released, a stop portion 248 on the top of the accumulator control-bar 137, adjacent to the recess 138, is brought into contact with the under side of the stud 140. In the movement of the accumulator to bring the pinions 64 into mesh with the sectors 16 the upper recess 152 in the extension 151 of the accumulator side plate 60 will have been turned into engagement with the roller 157 on the spring-pressed bell crank 154 which acts to hold the accumulator in its engaging position. The contact of the stop portion 248 with the stud 140 holds the accumulator control-bar 137 in neutral position until immediately after the operation of printing when the dog 148 will engage the stud 150 of the crank arm 129 and thereby rock the bell crank 120 rearward so as to draw the stop portion 248 from under the stud 140, whereupon the spring 144 will act to draw the accumulator control-bar 137 upward to bring the recess 138 in engagement with said stud 140, by which engagement the pinions 64 are held in mesh with the sectors 16. On the return movement of the crank handle 12 the sectors 16 are raised by the mechanism previously described, and while still in contact with the pinions of the adding wheels, thereby restoring the adding wheels to the position they occupied at the beginning of the operation. Just before the end of the rearward stroke of the crank handle the dog 147 engages the stud 149 of the crank arm 124, and by rocking the bell crank lever 120 will throw the accumulator control-bar 137 forward and thereby move the accumulator to carry the pinions 64 out of mesh with the sectors 16. In this movement the groove 153 will move into engagement with the roller 157 on the spring-pressed bell crank 154 which serves to hold the accumulator in its retracted or normal position. The adding wheels now show the total which has just been printed, and the machine is ready for the setting down and listing of a further sum which is added to the total, or rather sub-total in such an instance, previously struck, the grand total being held in the accumulator as a further sub-total or taken as a final grand total and the accumulator cleared, as desired.

In the operation of setting down an item, if an error is noticed before the crank handle has been pulled forward a distance sufficient to effect the engagement of the accumulator with the adding wheel sectors, the particular sector or sectors which may have been depressed to the wrong position can be readily moved up or down to the proper position, or in case a sector has been depressed in the wrong column, the same may be moved back to normal position and the proper sector depressed, owing to the yieldable engagement of the dogs 23 with the serrated edge portions 18 of the sectors. Hence, the necessity for providing a special error key and mechanism for accomplishing the purpose is obviated.

The construction and arrangement of the machine also permits the printing of an item without adding it, or in other words, without placing it in the accumulator. To accomplish this, the particular sector or sectors 16 having been depressed, the lever 31

is depressed until the roller 246 engages the stop plate 245, in which position the lever is held by the operator until the crank handle has been pulled all the way forward, during which time the printing of the item has been effected and the sectors restored to normal position. By so holding the lever 31, the accumulator control-bar 137 is held in neutral position so as not to engage either of the studs 140 or 141, and therefore the accumulator is not brought into engagement with the sectors.

I claim:

1. In an adding machine, the combination with a series of pivoted, toothed sectors and means for manually turning each sector through any required degree of its total arc of movement, of a pivotally mounted accumulator, a main actuating shaft and a crank handle for turning the same, mechanism actuated by said shaft in the forward movement of the crank handle to draw said accumulator into operative engagement with the sectors, and in the return movement of the crank handle to move the accumulator out of engagement with said sectors, a pivotally-supported bar extending underneath all of said sectors, spring-controlled lever mechanism connected with the supports of said bar, and means carried by said shaft and adapted to engage said lever mechanism in the return movement of the shaft to raise said bar and thereby return the sectors to zero in advance of the disengagement of the accumulator from the sectors and then to release the same to permit the bar to be turned to normal position by said lever mechanism.
2. In an adding machine, the combination with a series of pivoted, toothed sectors and means for manually turning each sector through any required degree of its total arc of movement, of a pivotally mounted accumulator, a main actuating shaft and a crank handle for turning the same, mechanism actuated by said shaft in the forward movement of the crank handle to effect operative engagement of the accumulator with the toothed sectors, and in the return movement of the crank handle to move the accumulator out of engagement with said sectors, a pivotally-supported bar extending underneath all of said sectors, spring-controlled lever mechanism connected with the supports of said bar, and a pivoted dog carried by said shaft and adapted to engage said lever mechanism in the return movement of the shaft to raise said bar and thereby return the sectors to zero in advance of the disengagement of the accumulator from the sectors and then to release the same to permit the bar to be returned to normal position by said lever mechanism.
3. In an adding machine, the combination with a series of pivoted adding wheel sec-

tors, each of which is manually movable through any required degree of its total arc of movement, of a main actuating shaft and a crank handle for turning the same, a pivotally-supported bar extending underneath all of said sectors, a toggle lever pivotally connected to the support of said bar, a contact member mounted on said toggle lever, a spring-controlled dog carried by said actuating shaft and movable in the forward movement of the crank handle to a position to engage said contact member and in the return movement of the crank handle to engage and straighten said toggle lever whereby to raise said bar and return the sectors to zero and then to release said contact member, and a spring for returning said toggle lever to its normal position.

4. In an adding machine, the combination with a series of pivoted, toothed sectors and means for manually turning each sector through any required degree of its total arc of movement, of a main actuating shaft, and means for returning the sectors to zero comprising a pivotally supported bar extending underneath all of said sectors, a toggle lever having one member pivotally connected to the support of said bar, a toe piece on the other member engaging a fixed part of the machine, a spring connected to the latter member and normally holding it in such engagement, a contact member on said toggle lever, a spring-controlled dog carried by said actuating shaft and movable in the forward movement of the main actuating shaft to a position to engage said contact member and in the reverse movement of the shaft to first engage and straighten said toggle lever whereby to raise said bar and return the sectors to zero, and then to release said contact member to permit said spring to return the toggle levers and said bar to normal position.

5. In an adding machine, the combination with a series of pivoted, toothed sectors and means for manually turning each sector through any required degree of its total arc of movement, of a pivotally mounted accumulator, a main actuating shaft and a crank handle for turning the same; a bar releasably engaging said accumulator, means actuated by the shaft for moving said bar to turn the accumulator into or out of operative relation with said sectors, a link pivotally connected at one end to said bar, and a depressible key lever pivotally connected to the other end of said link.

6. In an adding machine, the combination with a series of pivoted, toothed sectors, each of which is provided with a serrated rear edge, a series of spring-controlled pivoted dogs, each of which has a free end in frictional engagement with a serrated edge of a sector, means for manually turning each sector through any required degree of its total

arm of movement under the control of its dog, a bar extending over all of said dogs, and a pivotally mounted key lever connected to said bar for moving the same whereby, on 5 depressing said lever, said bar will be caused to move all of said dogs out of engagement with the serrated edges of the sectors and permit them to fall.

7. In an adding machine, the combination 10 with a series of pivoted, toothed sectors and means for manually turning each sector through any required degree of its total arc of movement, of a plurality of means yieldably engaging the respective sectors for 15 holding them in any position to which they may be moved, and means for simultaneously releasing all of said sectors.

8. In an adding machine, in combination 20 with sectors and means for manually actuating the same, an accumulator pivotally mounted in the machine involving carry-over mechanism, a main actuating shaft, means operated thereby for restoring the carry-over mechanism to normal, engaging members 25 located on opposite sides of the pivot of said accumulator, a pivotally-mounted bar releasably engaging one of the said engaging members, a link pivotally connected at one end to said bar, a key lever pivotally 30 connected to the other end of said link and depressible to move said bar into engagement with the other engaging member, an arm on said key lever, means operated by said shaft to actuate said bar to move the 35 accumulator into or out of operative relation with said sectors while said bar is in engagement with the first-named engaging member, and to move the accumulator out of mesh with the sectors when the bar is in engagement 40 with the other of said engaging members, and a stop on the actuating shaft in the path of said arm and preventing movement of said bar into engagement with the latter engaging member until the actuating 45 shaft has been turned to restore the carry-over mechanism to normal.

9. In an adding machine, the combination

with a series of pivoted adding wheel sectors, each of which is manually movable through any required degree of its total arc 50 of movement, of an actuating shaft, a listing sector formed as a unitary part of each adding wheel sector, a series of type bars slidably mounted in each listing sector, hammer mechanism including a series of hammers 55 adapted for coöperation with said type bars, means operated by said shaft for actuating said hammer mechanism, and mechanism controlled by said listing sectors and releasable thereby to place in operation the 60 hammers corresponding to the type sectors moved by the corresponding adding wheel sectors.

10. In an adding machine, the combination 65 with a series of pivoted adding wheel sectors, each of which is manually movable through any required degree of its total arc of movement, of a main actuating shaft, means for turning said shaft, a listing sector formed as a unitary part of and movable in 70 unison with each adding wheel sector, a series of spring-controlled type bars slidably mounted in each listing sector, hammer mechanism including hammers adapted to coöperate with the various type bars of the 75 respective listing sectors, means operated by said shaft for actuating the hammer mechanism, and a series of members, one of which is controlled by each listing sector and is adapted to be released by the movement of 80 the listing sector to place a corresponding hammer into operative relation with the hammer mechanism to be actuated thereby.

11. In an adding machine, in combination 80 with a rocking adding wheel sector, a listing sector constructed as a unitary part of the adding wheel sector and having a series of spring-controlled type bars slidably mounted therein at varying angles, permitting each of said type-bars to be brought to a substantially horizontal position.

In testimony whereof, I have hereunto set my hand.

WALTER F. McCaleb.
